United States Patent Office

Des. 228,605
Patented Oct. 16, 1973

228,605

PLATE OR THE LIKE

Ottorino N. Mercadante, Corning, N.Y., assignor to Corning Glass Works

Filed Jan. 12, 1972, Ser. No. 217,422

Term of patent 14 years

Int. Cl. D7—01

U.S. Cl. D7—36

Fig. 1

Fig. 2

FIG. 1 is a top plan view of a plate or the like of conventional configuration showing my new design.

FIG. 2 is an enlarged fragmental view of the plate and design shown in FIG. 1.

I claim:

The ornamental design for a plate or the like, as shown and described.
